(57) **CLAIM**

The ornamental design for a circular saw guide as shown and described.

DESCRIPTION

FIG. 1 is a top front side perspective view of a circular saw guide showing my new design;

FIG. 2 is a bottom rear side perspective view of the circular saw guide;

FIG. 3 is a front view of the circular saw guide, a rear view being identical;

FIG. 4 is a left side view of the circular saw guide, a right side view being a mirror image thereof;

FIG. 5 is a top view of the circular saw guide; and,

FIG. 6 is a bottom view of the circular saw guide.
